GENERATING SYSTEM

Robert R. Candor and Donald F. Alexander, Dayton, Ohio, assignors to General Motors Corporation, Dayton, Ohio, a corporation of Delaware

Original application May 20, 1937, Serial No. 143,843. Divided and this application December 18, 1937, Serial No. 180,637

19 Claims. (Cl. 171—313)

This application relates to refrigerating apparatus and more particularly to air conditioning for railway cars or the like.

This application is a division of our copending application Serial No. 143,843, filed May 20, 1937, now Patent No. 2,104,383.

This application is also related to application Serial No. 199,209 filed March 31, 1938, which is a continuation in part of this application. Application Serial No. 199,209 is directed primarily to the mechanical arrangement of the elements; whereas, this application is directed primarily to features of the electrical generation system; and application Serial No. 143,843, of which this application is a division, is directed primarily to the complete system including the air conditioning apparatus.

An object of this invention is to provide an electrically energized air conditioning system, in which the electrical energy is derived from the battery of the car while alternating current or relatively high voltage current is not available, and is derived from an alternating current, or relatively high voltage direct current while such current is available, in such a manner that energy derived from the alternating current, or relatively high voltage current may be used to charge the battery whether air conditioning is required or not.

Further objects and advantages of the present invention will be apparent from the following description, reference being had to the accompanying drawings, wherein a preferred form of the present invention is clearly shown.

In the drawings:

Fig. 1 is a diagrammatic representation of a car having a modified form of the invention;

Fig. 2 is a wiring diagram, in simplified form, for use with the system shown in Fig. 1;

Fig. 6 shows a modification of a portion of Figs. 2, 4, 5, 7, 8 and 9 to be used on electrified lines;

Fig. 3 is a detail of a modified form of clutch control;

Figs. 4, 5, 7, 8 and 9 inclusive show wiring diagrams to be substituted in the wiring diagram shown in Fig. 2, or Fig. 2 as modified by Fig. 6 and indicate different ways of governing generator output to balance the same with alternating current motor capacity; and

Fig. 10 is a diagrammatic showing of a shiftable brush commutator for a generator which may be used with this invention.

Railway cars, or other vehicles, have been provided heretofore with generating systems for

charging the battery on the vehicle, and have been provided with refrigerating apparatus being driven by a motor energized from the battery, or the generating system, while the vehicle is in motion and have also been provided with an alternating current, or relatively high voltage direct current, motor for driving the compressor of the refrigerating system while the vehicle is standing at the station, the arrangement being such that the alternating current, or relatively high voltage direct current, motor provides surplus energy for charging the battery. However, this charging operation has been made dependent on the operation of the compressor, so that battery charging could be obtained from the station current only while the compressor operates. According to this invention, however, it is possible to retain all of the advantages of the previous devices and at the same time provide for the charging of the battery independently of the operation of the compressor with substantially the same major equipment heretofore used.

In the modification shown in Figs. 1 and 2, the car 110 is provided with a refrigerating system 111 substantially similar in operation to the system shown and described as Figs. 1, 2 and 2a of application Serial No. 143,843 of which this is a division, and wherever numerals are used higher by 100 than those used in Figs. 1 and 2 of said parent application, it is intended to signify that the parts correspond in construction and function as nearly as possible. An axle-driven generator 115 charges the battery 114 while the car is running under the control of a voltage and current controller and a reverse current relay.

Fig. 6 shows how the system of Fig. 2, (or the systems of Figs. 4, 5, 7, 8 and 9) may be modified for use with electrified lines showing the trolley-like connection and the station plug similarly to Fig. 2a of said aforementioned parent application. In Fig. 6 the source of alternating current on the electrified line is likely to be very high voltage and therefore transformer 251 may be used, to be energized by the circuit from the wire 119a to the wheel 253. This provides alternating current of reduced voltage to the alternating current motor.

In the modification shown in Figs. 1, 2 and 6, the axle-driven generator 115 is adapted to be driven by an alternating current, or relatively high voltage direct current, motor 116 when the car is at the station or is on an electrified line. The arrangement is such that when alternating current is made available by inserting the plug 119 into the plug 120, or by connecting trolley-

like connector 120a to wire 119a or plug 120b to a plug at a station, the motor 116 drives the generator 115 all the time, thus charging the battery 114, and if the thermostat 113 requires it, 5 also driving the motor 112 and the compressor 117 to provide refrigeration. As indicated in Fig. 3, the generator 115 is provided with an electro-magnetic (or otherwise controlled) clutch 170 so that the generator 115 is disengaged from the 10 axle 171 whenever alternating current is available and the solenoid 173 is energized, and the electro-magnetic clutch 172 is caused to engage whenever alternating current is available and the solenoid 174 is energized. The construction 15 of clutches 170 and 172 may be similar, except that the clutch 170 is caused to be disengaged when its controller 173 is energized and the clutch 172 is caused to be engaged when its controller 174 is energized. The operation of 20 these clutches is such that the motor 116 is engaged with the generator 115 whenever alternating current is available and disengaged when the alternating current source is disconnected. The axle clutch 170 is disconnected when alternating current is made available so that the generator 25 115 may be driven by the motor 116, and this clutch is engaged when alternating current is disconnected. When the plug 119 is inserted in the receptacle 120, or the connector 120a is energized the controllers 173 and 174 are energized to 30 operate the clutches as heretofore described. In addition, the solenoid 175 is energized to close the starter contacts 176. The prongs of the jumper 180 are made shorter than the prongs 35 119c, thus insuring that good contact is made on the power lines before the starter is energized, and insuring operation of the clutches ahead of the alternating current motor. In Fig. 4, the motor starter may be provided with time-delay device 175a to insure operation of the clutches 40 before starting the alternating current motor. The refrigerating system is under the control of the thermostat 113 which is adapted to energize the starter solenoid 139 whenever the hand switch 136 and the head pressure and low pressure 45 switch 140 are closed. The energization of the solenoid 139, in response to refrigeration demand, progressively closes the contacts 146 to cause current to flow through the armature 148 of the direct current motor 112. At the same time, the motor field 149 is energized. The blower motor 129 and the compressor motor 112 are under the control of switch 143. The generator 50 115 may be provided with any type of voltage and current controller to connect the same with the battery 114 when the voltage across the armature of the generator is suitable for charging the battery and for disconnecting the same when the current reverses. Thus a coil structure 200 55 may be provided, which, by magnetic reaction with the potential coil structure 201, closes the switch 202 when the voltage across the armature of the generator 115 is suitable for battery charging. This operation places the generator in circuit with the battery. Immediately upon the 60 closing of the switch 202 the coil 203 is placed in the circuit. The coil 203 and the potential coil 204 independently regulate the resistance 205 in series with the field 206 by magnetic reaction with arm 205a in accordance with the normal 65 requirement of battery charging. Coil 203 also serves to hold shut the switch 202 during the battery charging period. The resistance 205 governs the strength of the field 206 which may be 70 the generator field or the generator exciter field, 75

and hence the generator output is regulated by the coils 203 and 204. Coil 204 limits the maximum voltage of the generator at any time, which value may be adjusted by a resistor in series with the coil 204 (not shown) or by an adjustable retaining spring device 207 cooperating with arm 205a. Coil 203 responds to all or a portion of the generator output current, and is magnetically connected to the resistance 205 so that generator current in excess of a predetermined value 10 through the coil 203 increases the value of the resistance 205 independently of the requirements of coil 204. This action limits the generator output current to any definite value regardless of maximum voltage adjustments. This may be accomplished by lost motion devices or other mechanical means between the armatures of coils 15 203 and 204 and the arm 205a.

When the generator output voltage decreases below that of the battery, the current through 20 switch 202 and coil 203 reverses. Coil structure 203 opens switch 202 by magnetic reaction with potential coil structure 201 preventing damage to the generator armature. An adjustable resistance 208 may be placed in parallel with the coil 25 203. This resistance 208 may be manually adjustable. This resistance 208 is used, in conjunction with coil 203, to regulate the total generator output current charging the battery.

The generator 115 may be of the type that produces current in the same direction regardless of the direction of rotation of the generator armature. This may be accomplished either by providing the usual brush shifting device, shown in Fig. 10, or it may be accomplished by providing 30 an exciter, the armature 209 of which reverses in rotation with reversal of generator armature rotation. The field 206 may be the exciter field. The exciter energizes the field 210 of the generator 115. If the usual brush shifting device is 40 used, as indicated in Fig. 10, the field 206 may be the field for the generator 115. In either case, the resistance 205 indirectly governs the output of the generator 115 to provide the proper current and voltage for the battery 114.

Means are provided for altering or biasing the control of generator 115 when alternating current is made available to balance the power demands of generator 115 with the power capacity of the motor 116. In the modification shown in Fig. 2, 50 this is accomplished by providing a biasing coil 211 adjacent the coil 203, the construction being such that the coil 211 is energized when the plugs 119 and 120 are joined. When this biasing coil 211 is energized, the pull of coil 203 upon the resistance 205 is altered, preferably to increase the resistance and thus reduce the field strength 206 which in turn reduces the current output of the generator 115. The energization of the coil 211 is made dependent on the energization of the 60 starter coil 175 which closes the contacts 212 thus placing the coil 211 across the battery.

In Fig. 4 a slightly different method of energizing the coil 211a, which corresponds to coil 211 of Fig. 2, is provided. In this case the plug 1119 is provided with a jumper 213 which places the coil 211a across the battery when the plug 1119 is connected to the plug 1120.

In the modification shown in Fig. 5, the biasing coil 211b, which corresponds to the coil 211 of Fig. 2, is energized by causing the current coil 214 to close the contacts 219, thus placing the coil 211b across the battery. The remaining portions of Figs. 4 and 5 are to be combined or substituted 70 75

in the wiring diagram shown in Fig. 2, and the operation of the parts is substantially the same.

In Fig. 7, instead of providing a biasing coil similar to coil 211 of Fig. 2, the resistance 208a is made automatically adjustable, so that it is automatically altered whenever alternating current is made available. Thus the switch 215 is automatically opened by the energization of the starter coil 175 when alternating current is made available, and this places the entire portion of the coil 208a in parallel with the coil 203. This causes a greater proportion of current to flow through the coil 203 and hence increases the magnetic pull on the arm of the resistance 205. This weakens the field 206 and reduces the output of the generator 115 while it is being driven by the motor 116.

In Fig. 8, the coil 203c is modified directly when alternating current is made available. Thus when the starter field 175 is energized, the contacts 216 are closed, thus shunting a portion of the coil 203c and increasing its pull on the resistance 205 to reduce the output of the generator 115 while being driven by the motor 116.

The motor 16 and motor-generator 12 may be combined in a single dynamo electric machine having a single shaft. Likewise, the motor 116 and generator 115 may be combined in a single dynamo electric machine having a single shaft.

In the modification shown in Fig. 9, an additional resistance 217 is provided in parallel with the resistance 208. When the starter coil 175 is energized, the contacts 218 are opened thus decreasing the resistance which is in parallel with the coil 203. This increases the current flowing through the coil 203 to increase the resistance 205 as previously pointed out. In this modification, or in any of the preceding modifications of Figs. 2 to 8 inclusive, the jumper 180 may be omitted, and the starter coil 175 may be made responsive to current across the leads between the plug and the starter contacts without the use of the jumper. In such a case the motor starter may be provided with a time delay device, diagrammatically indicated at 175b.

In the modification shown in Fig. 3, the clutch 170a, between the axle and the generator 115a is controlled by solenoid 173a energized by a small generator 181 driven in proportion to car speed. The clutch 170a is automatically disengaged when the car stands or travels below a relatively low speed limit, such as 10 M. P. H., and is engaged at all speeds above that limit. The clutch 172a is controlled by the solenoid 174a to be engaged when the car stops or travels below some speed limit as 10 M. P. H. The remainder of the system is the same as in Figs. 1 and 2 except that the clutches 170 and 172 and solenoids 173 and 174 are replaced by the modified form of Fig. 3.

While the clutches have been indicated, in some instances, to be pneumatically controlled by the operation of solenoid valves, and have been indicated, in other instances, to be directly operated by the solenoid, it is to be understood that these forms may be used interchangeably or may be replaced by equivalent features. The clutch between the generator 115 and motor 116 may be omitted if desired. The clutch 170 may be a centrifugal, non-electric clutch, automatically disengaging below some car speed, such as 10 M. P. H. If a centrifugal clutch is used, the solenoid 173 may be omitted. The clutch 172, together with its solenoid control 174 or 174a may be omitted entirely, in which case the alternating current motor may be placed between the di-

rect current generator and the live axle assembly, or the alternating current motor and direct current generator can be made into a unitary machine. The exciter 209 may be built in with the direct current generator 115 as a unitary machine.

Fig. 10 shows the usual shiftable brush arrangement for a direct current generator to cause the generator to charge the battery regardless of direction of rotation of the armature. Fig. 10 indicates how such an arrangement is fitted into the wiring diagrams of Figs. 1 to 9 inclusive, instead of the exciter circuit. The well-known shiftable brush carriage 115a has its brushes connected to the flexible cables 115b and 115c which are connected to the generator leads for charging the battery. The carriage 115a automatically shifts the brushes with a change in rotation to maintain the direction of current constant. Sufficient parts of the wiring diagram of Figs. 1 to 9 are shown to indicate the substitution.

In Fig. 2, a voltage regulator 150 has been indicated to maintain a constant voltage supply to the fan motor 129, lights 151, etc. The lights are provided with switch control 152. The various motors may be provided with overload cutouts. Thus an overload switch 176a may be provided to protect motor 116, and an overload switch 60a may be provided for motor 16.

While the form of embodiment of the invention as herein disclosed, constitutes a preferred form, it is to be understood that other forms might be adopted, all coming within the scope of the claims which follow.

What is claimed is as follows:

1. In a generating system for a vehicle having a live axle, a generator, means for driving said generator from said live axle, an alternating current motor for driving said generator, and means for automatically reducing the generator output when changing from said live axle drive to said alternating current motor drive.

2. In a generating system for a railway car or the like, an axle driven direct current generator, an alternating current motor on said car drivingly connected to said direct current generator, a source of alternating current, a connector for connecting said source of alternating current to said alternating current motor, means whereby said alternating current motor drives said direct current generator independently of said axle, voltage and current controlling means for said direct current generator, and means modifying said voltage and current controlling means while said direct current generator is driven by said alternating current motor.

3. In a generating system for a railway car or the like, an axle-driven direct current generator, a battery in electrical circuit with said generator, an alternating current motor on said car drivingly connected to said direct current generator, a source of alternating current, a connector for connecting said source of alternating current to said alternating current motor, means whereby said alternating current motor drives said direct current generator independently of said axle when said connector is connected to said source of alternating current, a field for said direct current generator, coil means controlling the strength of said field whereby the output of said direct current generator is controlled while said direct current generator is driven by said axle, and means modifying the action of said coil

means while said direct current generator is driven by said alternating current motor.

4. In a generating system for a railway car or the like, an axle-driven direct-current generator, a battery, automatic regulating means connecting said generator and battery while said generator is being driven at sufficient speed and controlling the voltage and current output of said generator, an alternating current motor drivingly connected to said direct current generator, and provisions for disconnecting said direct-current generator from said axle and for modifying said automatic regulating means while said alternating current motor is energized and drives said direct current generator.

5. In a generating system for a railway car or the like, an axle-driven direct current generator, a battery, coil means automatically connecting said generator and battery while said generator is being driven at sufficient speed and controlling the voltage and current output of said generator, an alternating current motor drivingly connected to said direct current generator, and provisions for disconnecting said direct current generator from said axle and for modifying said coil means while said alternating current motor is energized and drives said direct current generator.

6. In a generating system for a railway car or the like, an axle-driven direct current generator, a battery, automatic regulating means connecting said generator and battery while said generator is being driven at sufficient speed and controlling the voltage and current output of said generator, means automatically maintaining the same direction of current of said direct current generator while its armature is rotated in either direction, an alternating current motor drivingly connected to said direct current generator, and provisions for disconnecting said direct current generator from said axle and for modifying said automatic regulating means while said alternating current motor is energized and drives said direct current generator.

7. In a generating system for a railway car or the like, an axle-driven direct current generator, a battery, automatic regulating means connecting said generator and battery while said generator is being driven at sufficient speed and controlling the voltage and current output of said generator, an alternating current motor drivingly connected to said direct current generator, a connector for connecting said alternating current motor to a source of alternating current, a coil energized by the connection of said connector to said source of alternating current, said coil modifying said automatic regulating means.

8. In a generating system for a railway car or the like, an axle-driven direct current generator, a battery, automatic regulating means connecting said generator and battery while said generator is being driven at sufficient speed and controlling the voltage and current output of said generator, an alternating current motor drivingly connected to said direct current generator, a clutch between said axle and said direct current generator, means automatically disconnecting said clutch during the time said alternating current motor is energized, and means automatically modifying said automatic regulating means during the time said alternating current motor is energized.

9. In a generating system for a railway car or the like, an axle-driven direct current generator, a battery, automatic regulating means connect-

ing said generator and battery while said generator is being driven at sufficient speed and controlling the voltage and current output of said generator, an alternating current motor drivingly connected to said direct current generator, a connector for connecting said alternating current motor to a source of alternating current, a coil energized by the connection of said connector to said source of alternating current, said coil governing a switch to modify said automatic regulating means.

10. In a generating system for a railway car or the like, an axle-driven direct current generator, a battery, automatic regulating means connecting said generator and battery while said generator is being driven at sufficient speed and controlling the voltage and current output of said generator, said automatic regulating means comprising a voltage coil and a current coil, an alternating current motor drivingly connected to said direct current generator, a connector for connecting said alternating current motor to a source of alternating current, a coil energized by the connection of said connector to said source of alternating current, said coil modifying the action of said current coil whereby the output of said direct current generator is reduced.

11. In combination, a generator, a battery adapted to be charged by said generator, a high power source for driving said generator, a low power source for driving said generator, a regulator unit controlling the output of said generator, and means automatically causing said regulator unit to change the standard of regulation as a changeover is made from driving the generator by the one power source to driving the generator by the other power source.

12. In combination, a railway car or the like having a rotating part, a direct-current generator, torque transmitting means between said part and said generator, a battery adapted to be charged by said generator, a regulator unit controlling the output of said generator, auxiliary means for driving said generator, and means adjusting the standard of regulation of said regulator unit in response to a change-over from one driving means to the other whereby the output of said generator is greater when driven from said rotating part than when driven from said auxiliary driving means.

13. In combination, a generator, a battery adapted to be charged by said generator, a high power source for driving said generator, a low power source for driving said generator, a regulator unit for said generator, and means for adjusting the standard of regulation in accordance with the capacity of the power source driving said generator.

14. In combination, a generator, a battery adapted to be charged thereby, a plurality of means for driving said generator, a generator regulator unit, and means whereby a changeover from one of said driving means to another of said driving means changes the standard of regulation of said regulator unit.

15. In combination, a generator, a battery adapted to be charged thereby, a high power source for operating said generator, a low power source for operating said generator, a generator regulator unit automatically controlling the generator output, and means automatically controlling said regulator unit to restrict the generator output to a safe value for both the generator and the limited power source when operating from said limited power source.

16. In a generating system for a railway car or the like, an axle driven direct-current generator, a battery adapted to be charged thereby, automatic regulating means having a voltage coil and a current coil connecting said generator and battery while said generator is being driven at sufficient speed and controlling the voltage and current output of said generator, an alternating-current motor drivingly connected to said direct-current generator, a connector for connecting said alternating-current motor to a source of alternating current, a solenoid energized by the connection of said connector to said source of alternating current, and means governed by said solenoid for shortcircuiting a portion of one of said coils during the time said alternating-current motor is energized.

17. A generating system for a railway car or the like, an axle driven direct-current generator, a battery, automatic regulating means connecting said generator and battery while said generator is being driven at sufficient speed and controlling the voltage and current output of said generator, said means comprising a voltage coil and a current coil, resistance means in parallel with one of said coils, an alternating-current motor drivingly connected to said direct-current generator, a connector for connecting said alternating-current motor to a source of alternating current, a solenoid energized by the connection of said connector to said source of alternating current, and means operated by said solenoid for

changing the amount of resistance in parallel with said coil when said alternating-current motor is deenergized.

18. In a generating system for a railway car or the like, an axle driven direct-current generator, a motor on said car drivingly connected to said direct-current generator, a source of current, a connector for connecting said source of current to said motor, means whereby said motor drives said direct-current generator independently of said axle, voltage and current controlling means for said direct-current generator, and means modifying said voltage and current controlling means while said direct-current generator is driven by said motor.

19. A battery charging mechanism for railway cars or the like comprising a direct-current generator adapted to be driven from the car axle, an alternating-current motor drivingly connected to said direct-current generator, means for connecting said alternating-current motor to a source of alternating current, means whereby said alternating-current motor drives said direct-current generator independently of said axle, voltage and current controlling means for said direct-current generator, and means modifying said voltage and current controlling means while said direct-current generator is driven by said alternating-current motor.
